CONTROLLED VOLUME STEAM HEATING
SYSTEM

Paul B. Parks, Oak Park, and Emil E. Stenzel,
Chicago, Ill., assignors to Vapor Car Heating
Company, Inc., Chicago, Ill., a corporation of
New York

Application May 17, 1940, Serial No. 335,720

10 Claims. (Cl. 237—6)

This invention relates to a new and improved controlled volume steam heating system, more particularly to a heating system especially useful on railway passenger cars where, due to the increasing number of compartments or zones in the car, each requiring separate and individual controls, a heating system has become desirable in which a number of separate radiators can be supplied with steam from one controlling regulator through the medium of one common feed pipe in which a substantially constant volume of steam is maintained automatically at a substantially constant and relatively low pressure.

With the conventional vapor heating systems as used in the past, the practice has been to connect all the radiators in series, and in order to overcome the excessive resistance in such a system a steam pressure in excess of that actually required for radiating purposes has been necessary at the inlet end of the radiating system despite the fact that the discharge end is open to the atmosphere. This excessive pressure has created a number of difficult problems in maintaining a satisfactory automatic control system.

The present new system comprises, in addition to a source of steam at a relatively high pressure, a main feed or supply pipe from which all of the separate radiating devices are individually supplied with steam, there being a feed regulator between the source of steam and the supply pipe and cooperating retarding devices at the outlets of the radiators, and at the outlet end of the supply pipe for maintaining a substantially constant volume of steam in the supply pipe at a predetermined low but super-atmospheric pressure sufficient to overcome the resistance in each of the separate radiating devices. The condensate from all parts of the system is preferably discharged through a single drip member, and the retarding device at the outward end of the supply pipe is adapted to permit a small but adequate flow of steam into the return and drip connections so as to keep these pipe connections warm and prevent freezing of any liquid therein.

None of the returning condensate or gases come in contact with the thermostatic device of the steam regulator which governs the flow of steam from the source to the supply pipe.

The steam regulator used in this system is very sensitive and comprises a positive shut-off valve coupled to a thermostatic bellows that allows the valve to open wholly or partially as may be necessary as the bellows contracts. The bellows is surrounded by a fined housing to ac-

celerate the heat dissipation and is adapted to move the valve to a modulated or balanced position so as to permit just sufficient flow of steam into the supply pipe to maintain the desired volume of steam therein at the desired low pressure. In a conduit leading from the low pressure side of the regulator to the chamber containing the thermostatic bellows, and forming substantially a part of the regulator, is positioned a limiting valve adapted to partially open and permit a restricted flow of steam to the thermostatic chamber when the steam pressure at the outlet side of the regulator and in the supply pipe has risen to a predetermined desired low pressure, for example, five pounds to the square inch. This restricted flow of steam to the bellows chamber will be modulated so as to cause just sufficient expansion of the bellows or "economy diaphragm" to move the cut-off valve to a balanced position just adequate to permit the desired steam flow into the supply pipe.

Since all of the condensate and discharged fluids returned from the radiating systems and the supply pipe are discharged through a common, heated drip connection without any contact with the diaphragm or bellows of the regulator, there is no disturbing factor due to the presence of these relatively cold fluids which would upset the delicate balance of the steam regulator.

Due to the fact that the radiator valves are separately operated by individual thermostats and therefore turn on and off frequently, the demand on the steam supply in the main supply pipe will vary considerably at different times and it will be evident that the steam regulator must be quite sensitive so as to maintain the desired volume of steam in the supply pipe at all times, and the mechanism assembly hereinafter described is designed to maintain this desired condition.

Means is also provided for keeping steam out of the branch supply pipes or risers, and the inlet valve, leading to the respective radiators or radiating systems, when the inlet valves are closed, thus eliminating undesirable heating from these pipes and valves when no additional heat is desired in the spaces heated by such radiating systems.

The principal object of this invention is to provide an improved controlled volume steam heating system of the type briefly described hereinabove and disclosed more in detail in the specifications which follow.

Another object is to provide an improved means for maintaining a substantially constant volume

of steam supply at a predetermined low but super-atmospheric pressure, for delivering steam to the several radiators.

Another object is to provide improved means for preventing undesired heating from the steam supply connections leading to the individual radiators.

Another object is to provide means for warming the drip connections leading from the several parts of the heating system so as to prevent freezing in the exposed piping.

Other objects and advantages of this invention will be more apparent from the following detail description of certain approved forms of apparatus designed and assembled so as to operate according to the principles of this invention.

In the accompanying drawings:

Fig. 1 is a diagrammatic elevation showing a portion of one approved form of the heating system.

Fig. 2 is an elevation, similar to Fig. 1, showing a somewhat modified form of system in which shorter supply and return pipes are used.

Fig. 3 is a longitudinal vertical section, on a larger scale, through one of the solenoid-controlled radiator inlet valves, together with a portion of one of the radiators supplied with steam from this valve.

Fig. 4 is a partial view of the piping connections for conducting steam from the main supply pipe to the radiator inlet valve.

Fig. 5 is a longitudinal vertical section, on a larger scale, through the water-seal device used in these supply connections, this view being taken substantially on the line 5—5 of Fig. 4.

Fig. 6 is a wiring diagram showing the electrical connections for controlling the valve shown in Fig. 3.

Fig. 7 is a longitudinal vertical section through the steam regulator, this view being taken substantially on the line 7—7 of Fig. 1 but on a much larger scale.

Fig. 8 is a longitudinal vertical section through the pressure limit valve.

Fig. 9 is a transverse vertical section through this valve taken substantially on the line 9—9 of Fig. 8.

Fig. 10 is a longitudinal vertical section through the retarding valve used at the end of the supply pipe.

Fig. 11 is a detail perspective, partially in central section, through a different form of outlet port and valve-seat for use in the valve shown in Fig. 10.

Referring first to the general assembly shown in Fig. 1, the improved heating system comprises, in general, the main source of high pressure steam A which delivers steam through suitable valved connections including the main steam regulator B to the steam supply pipe C from which steam is individually supplied to each of the several radiating systems. The trap or steam-retarder D at the end of supply pipe C cooperates with the pressure limit valve E to control the steam regulator B and keeps the supply pipe C filled with steam at a predetermined low but super-atmospheric pressure. Each radiator F is supplied with steam through an electrically controlled inlet valve G, the steam flowing from supply pipe C through a branch supply pipe or riser connection including the water-seal H, the function and operation of which will be hereinafter described in detail.

The condensate from the radiator drains out through a return branch connection including

the retarding device J into the main return pipe K from which the water drains out to the atmosphere through the drip pipe L. The condensate from the steam used in controlling the steam regulator B also flows out through this drip device L. The retarding device D not only holds back the steam in supply pipe C so as to help in maintaining the desired pressure in this pipe, but also functions like a trap to permit the escape 10 of condensate formed in this supply pipe C, and also permits a limited flow of steam, as well as this condensate, into the return pipe K, this restricted steam flow serving to keep the return pipe and drip connection L at a sufficiently warm temperature to prevent freezing of liquid in these exposed pipes. The floor of the car is indicated at 1, the spaces in the car being divided by vertical walls or partitions 2 into separate compartments each of which contains and is heated by one of the radiators F. A thermostat M positioned in this compartment and responding to temperature changes therein serves, through suitable electrical connections, to control the inlet valve G.

25 The source of steam A, as here shown, is the main train-pipe which extends throughout the length of the train and is supplied with steam from the locomotive. The steam in this pipe will normally be under a rather high pressure, for example 250 pounds. A branch supply pipe 3 leads from train pipe A to the main inlet port of the steam-regulator B. In this pipe 3 is located a main cut-off valve 4 which will normally be open, and a reducing valve 5 adapted to materially reduce the pressure of the steam supply to the regulator B, for example to about 20 pounds per square inch. In order to have this regulator B operate to the best advantage it is desirable not to supply steam thereto at too high a pressure, and for this reason the reducing valve 5 is interposed between the main steam source and the regulator.

30 The steam-regulator B operates similarly to so-called "vapor regulators" already known in the art, except that this regulator is preferably much more delicate in its operation so that the main control valve which is usually moved abruptly from a fully closed to a fully open position may be adjusted to selected partially closed 35 positions so as to modulate or reduce the steam flow through the regulator without entirely opening or closing the valve. The improved regulator as partially shown in Fig. 7 is substantially of the type disclosed and claimed more in detail in the copending application of Parks and Peterson, Serial No. 288,104, filed August 3, 1939. For the present purposes this regulator may be briefly described (referring to Figs. 1, 2 and 7) as comprising a casing 6 supported by a suitable bracket 7 and formed with an inlet chamber 8 into which steam flows through port 9 from the supply pipe 3. The steam flows from inlet chamber 8 through strainer 10 and passage 11 into the outlet chamber 12 and thence through port 13 into the inlet end portion of supply pipe C from which the radiators are supplied. Steam also flows from outlet chamber 12 through a second port similar to 13 but disposed in the opposite wall of chamber 12, and thence through pipe 14 (Fig. 1) into the pressure-limit valve E, hereinafter described. The movable valve member 15 is guided in cage 16 so as to engage and cooperate with valve seat 17 at the outlet of passage 11 to cut off the flow of steam from inlet chamber 8 into outlet chamber 12. The spring 18 surrounding valve

stem 19 tends to move valve 15 toward the open position shown in Fig. 7.

A thermostatic member indicated generally at 20 is housed in a chamber 21 formed in a separate casing 22 provided with a plurality of outside radiating ribs 23 so as to expedite the lowering of the temperature around the thermostatic member when steam is no longer admitted to the thermostat chamber 21. Thermostatic member 20 comprises an outer bellows diaphragm 24 and contains a quantity of heat-responsive fluid so that when the thermostatic member is directly exposed to steam it will expand thereby forcing outwardly (to the right Fig. 7) the stem 25 which projects through a sealing member 26 and engages at its outer end the lower arm 27 of a lever pivoted adjustably intermediate its length at 28. The upper arm 29 of this lever is adapted to engage and push inwardly (toward the left Fig. 7) the stem 30 which projects into sealing member 31 and is adapted to engage valve stem 19 and force the valve 15 toward its seat against the opposition of spring 18.

In the usual vapor-regulator as used in an ordinary vapor heating system, after the radiating system has been filled with steam the excess steam will flow back through a return pipe into the chamber housing the thermostatic member and thereby close the valve 15 so as to cut off further flow of steam into the radiating system. In the present improved system, steam and other fluids returned from the radiating system or systems do not flow back into thermostatic chamber 21 but are separately disposed of as hereinafter described. In this present improved system the outlet ends of the supply pipe C and the several individual radiating devices are not directly open to the atmosphere but on the contrary the outflow of steam is substantially prevented by the retarding devices D and J respectively. As a consequence, as further steam is admitted from the source to pipe C through regulator B, the pressure of the steam in supply pipe C and the supply chamber 12 of the regulator will be built up. At the same time steam at this same increased pressure will flow from outlet chamber 12 of the regulator through pipe 14 into the pressure limit valve E shown more in detail in Figs. 8 and 9.

This improved pressure limit valve E comprises a main casing 32 formed at opposite ends and at one side with three alternative threaded ports 33, 34 and 35 all leading into or from the steam chamber 36 separated by internal web 37 from the upper outlet steam chamber 38. The pipe 14 leading from chamber 12 of the regulator B extends into one of the inlet ports 33, 34 or 35. In the example here shown pipe 14 is threaded into the port 35. The other two ports 33 and 34 are closed by suitable plugs 39. Alternatively, this pressure-limit valve might be inserted midway the length of a pipe without interfering with the free flow of steam through this pipe, in which case the two sections of the pipe would be connected into the opposite pair of ports 33 and 35. A pipe 40 leads from the outlet port 41 of the upper steam chamber 38 down into the inlet port 42 of the thermostat chamber 21 of regulator B (see Fig. 1), this port 42 being opposite the similar outlet port 42' shown in Fig. 7.

A cage structure 43 is threaded at its lower end 44 in a vertical passage formed in web 37, this cage having a central passage 45 closed at its lower end by the perforated strainer 46 and

formed at its upper end with valve seat 47. Open passages 48 in the sides of cage 43 permit steam to flow from passage 45 into the upper steam chamber 38. The valve 49 which cooperates with valve seat 47 is carried by stem 50 slidable through guide-plug 51 mounted in the upper end of cage 43. The compression spring 52 is confined between a pair of similar spring-cups 53 and 54, the cup 54 being held between the nuts 55 adjustably threaded on the upper end portion of valve stem 50. The spring-cup 53 bears against the under surface of the closure plate 56 held by screw bolts 57 against a gasket 58 to close the open upper end of the main valve casing 32. The spring 52 will be so adjusted (by changing the position of nuts 55) that the valve 49 will be held down against seat 47 until a predetermined steam pressure, for example 5 pounds, is built up in the lower steam chamber 36, which pressure will correspond with the pressure in outlet chamber 12 of the steam regulator B, and also the pressure in supply pipe C. As this steam pressure rises above this pre-determined pressure the valve 49 will be lifted from its seat against the opposition of spring 52 so as to admit steam into the chamber 38 from which this steam will flow through pipe 40 into the thermostat chamber 21 of the regulator B. The spring 52 is of such a type that the spring-load will increase rapidly as the spring is compressed, consequently the valve 49 will only be lifted slightly from its seat so as to permit only restricted flow of steam through the conduit hereinabove described to the thermostat chamber of the regulator. As a consequence the thermostatic bellows will only be slightly expanded so as to only partially close the valve 15 and decrease the flow of steam into chamber 12 and supply pipe C. The parts will quickly assume a balanced position in which valve 15 is only open to an extent sufficient to admit enough steam to keep up the desired steam pressure (for example 5 pounds per square inch) in the supply pipe C. Obviously, as a greater or lesser number of radiators F are supplied with steam from supply pipe C, the volume of steam admitted to pipe C must be increased or decreased, and a rebalancing of the regulator B will be necessary each time a radiator is put in or out of service. Since the electrically controlled valves G are rather frequently opened and closed by the thermostatically controlled connections as hereinafter described, it will be apparent that a more or less constant rebalancing of the regulator B is required in order to control the volume of steam available in supply pipe C at a relatively constant low pressure. However, since none of the returned fluids, at low temperature, are returned to the regulator B as in the ordinary vapor heating system, the required balance in regulator B is much more accurately and simply maintained since all of the steam which controls the expansion of thermostatic bellows 20 comes directly from supply chamber 12 through the pressure-limit valve E.

One of the individual radiating systems will now be described, it being understood that there will be one of these systems for each separate compartment of the car, and as many as six or more of these separate systems can be individually supplied with steam from the same supply pipe C. A preferred form of inlet valve G and radiator F is indicated in Fig. 3, the valve being shown in more detail and claimed in the co-

pending application of Parks and Peterson, Serial No. 335,719, filed of even date therewith.

While any suitable type of radiators might be used, the preferred form of radiators F as here shown are of the "inner-feed" type (Figs. 1, 2 and 3) comprising a pair of concentric or co-axial pipes 59 and 60, the outer pipe 60 being provided with a plurality of radiating fins 61 and being closed at one end by a cap member 62. Steam flows from the outlet chamber 63 of valve G through outlet port 64 into which the inner end 65 of the inner radiator pipe 59 is threaded and thence through pipe 59 which terminates short of the cap 62. The steam then flows back through the annular space 66 between pipes 59 and 60 into the discharge chamber 67 of the valve and out through the branch return pipe 68. The outer radiator pipe 60 is threaded into the inlet port 69 of chamber 67. The main valve casing 70 is formed with a steam chamber 71 into which steam is delivered through inlet port 72 from the supply pipe 73 extending from the main supply pipe C. A passage 74 extends from chamber 71 to the outlet chamber 63 from which steam is delivered to the inner radiator pipe 59 as already described. A cage structure 75 has a hollow nipple 76 threaded into the inlet end of passage 74, and a movable valve member 77 guided in cage 75 is adapted to engage valve seat 78 in the cage and cut off the flow of steam into the radiator. When the valve 77 is moved back from seat 78 steam will flow from supply chamber 71, as already described, into and through the radiator F. When valve 77 is closed against the valve seat 78 the supply of steam to the radiator F will be cut off. The valve stem 79 extending rearwardly from valve 77 is slidably guided through the rear head portion 80 of the cage, and valve stem 79 carries at its outer end a collar member 81 comprising an outstanding flange or projection 82 which forms a portion of the manually operated valve-moving mechanism hereinafter described. A compression spring 83 is confined between the end of the cage and collar 81, this spring normally functioning to move valve 77 to the open position shown in Fig. 3. A solenoid assembly indicated generally at 84 is fitted at one end into casing 70 against gasket 85 so as to close this end of steam chamber 71. The circuit wires 86 and 87 extending from the opposite ends of the solenoid coil 88 lead out through the conduit 89. The movable core 90 of the solenoid will be drawn in (toward the left Fig. 3) when the solenoid is energized, and the bearing rod 91 extending from one end of core 90 will engage the end of valve stem 79 and force the valve 77 to closed position against the opposition of spring 83. The valve will be held in this closed position as long as the solenoid 88 remains energized. When the energizing circuit is broken, the spring 83 will automatically open the valve.

A typical circuit for thermostatically actuating and controlling this valve is shown diagrammatically in Fig. 6. The thermostat indicated generally at M (see also Fig. 1) is positioned at some suitable location in the compartment or space heated by radiator F, this thermostat comprising a mercury column 92 which is always in engagement with a lower fixed contact 93 and which engages an upper fixed contact 94 at some predetermined temperature. An auxiliary heating coil 95 is associated with the thermostat, this coil being energized over the following circuit: From power main 96 through wire 97, coil 95,

wire 98, rheostat 99, and wire 100 to the other power main 101. The strength of the current in heating coil 95, and hence the amount of heat added to the thermostat, will depend upon the manual adjustment of rheostat 99 which will be suitably calibrated so that a plurality of desired temperatures may be selected within the compartment. While the thermostat M is directly responsive to temperature changes within the compartment, the actual compartment temperature at which the mercury column will engage the upper fixed contact 94 is dependent upon the amount of auxiliary heat added to the thermostat by coil 95. The relay coil 102 is normally energized over the following circuit: From main 96 through resistance 103, relay terminal 104, relay coil 102, relay terminal 105, and resistance 106 to the other power main 101. When the relay is so energized it will lift the core 107 so as to open the switch 108 and thus deenergize the valve solenoid 88 which is controlled through the following circuit: From main 96 through wire 109, switch 108, wire 86, solenoid coil 88, and wire 87 to the other main 101. With solenoid 88 deenergized, the spring 83 will open the valve 77 and admit steam to the radiator F. When the desired temperature is reached in the compartment, the mercury column 92 will engage the upper thermostat contact 94 and thus complete a shunt circuit as follows: From one terminal 104 of the relay coil through wire 110, mercury column 92, and wire 111 to the other terminal 105 of the relay. This will deenergize the relay so that switch 108 will automatically close and solenoid 88 will be energized to close valve 77 and cut off the flow of steam to the radiator. Similarly, when the temperature within the compartment falls below the temperature for which thermostat M is set, the shunt circuit will be broken and relay 102 will again be energized to open switch 108 and deenergize solenoid 88 so that spring 83 will again open the valve 77 and admit more steam to the radiator. This is the position of the parts indicated in Fig. 6.

The valve G can also be manually operated. Referring to Figs. 1 and 3, a disk 113 is fixed on an operating shaft 114 extending transversely through the upper portion of steam chamber 71. An arcuate recess 115 is formed within one peripheral portion of disk 113, and the flange or projection 82 on collar 81 of the valve stem assembly extends into the arcuate recess 115. When disk 113 is in the central position indicated in Fig. 3 the core 90 and valve 77 can be reciprocated longitudinally so as to open or close the valve under the electrical control hereinabove described. A locking detent 116 is guided for longitudinal movement within the screw-plug 117 and is urged downwardly by spring 118 into yielding engagement with one of the series of recesses 119, 120 and 121 formed in the upper peripheral portion of disk 113. When detent 116 engages the central recess 120, the disk will be held in the intermediate position shown in Fig. 3 and the valve will be under electrical control. When disk 113 is swung through a suitable arc in a clockwise direction, the shoulder 122 at one end of recess 115 will engage the projection or flange 82 and shift the movable assembly consisting of collar 81, stem 79 and valve 77 toward the left (Fig. 3) against the opposition of spring 83, until detent 116 is moved into recess 119 thus yieldably locking the valve in closed position. On the other hand, if the disk 113 is swung through an equal arc in the counter-clockwise direction, shoulder 123 at the

other end of the recess 115 will be moved into proximity to collar 82 and the detent 116 will be snapped into the other recess 121 thus locking the valve in open position, even though solenoid 88 should be energized. A crank or lever 124 (Fig. 1) secured on one outer end of shaft 114 is adapted to shift the disk from one to another of the three positions hereinabove described, these three positions of the valve being suitably indicated by handle 124 on a dial formed on the outer surface of the valve casing.

Referring now more particularly to Figs. 1, 4 and 5, steam from the main supply pipe C flows to the radiator F through the branch supply pipe 73 which is connected at its discharge end into valve G as just described, and which receives steam at its inlet end from the water-seal fitting H connected at an intermediate point in main supply-pipe C. As shown in Fig. 4, this branch supply pipe 73 will usually be of greater length than appears in Fig. 1 since the supply pipe C will be beneath the central portion of the car whereas the radiator F and valve G are positioned near one side wall of a compartment, thus requiring an intermediate laterally extending portion 73' of pipe 73 (see Fig. 4). The fitting H is formed centrally to enclose a steam chamber 125 having aligned ports 126 and 127 in opposite sides thereof into which are fitted the adjacent ends of the two sections of supply pipe C. A depressed central portion 128 of the fitting H, closed at the bottom by a removable plug 129, serves to hold an accumulated pool of condensate 130. A cup-shaped web 131, open at its lower end 132 beneath the level of pool 130, projects downwardly from the upper portion of casting H within the steam chamber 125, this web enclosing a central outlet chamber 133 having an upper outlet port 134 into which the lower end of branch pipe 73 is secured. A quite small vacuum-breaking vent 135 is formed in one side wall of web 131 above the water level of the pool and connecting the inner and outer steam chambers 133 and 125.

The function of this water-seal H is to prevent undesired heating of the compartment when the valve G is closed. It will be noted that if, as usual, the inlet valve G were connected directly with the supply pipe C through a branch riser, steam would still be supplied to the steam chamber 71 of the valve G through riser 73 even when valve 71 is closed. As a consequence, all of the branch supply pipes 73 as well as a large portion of the valve casting would be filled with steam at all times and heat from this steam would be transmitted even to the inlet end portion of radiator F. As a result there would be a partial heating of the compartment even at such times as no heating was required or desired. Referring now to the operation of the water-seal H, but neglecting for the moment the vent 135 and its function, when the electrically controlled inlet valve is closed the steam in valve chamber 71 and supply pipe 73 will condense thus forming a partial vacuum which will draw up the condensate thus formed as well as the water at the water-seal. As additional steam is condensed in this branch pipe it will be drawn up so as to eventually form a substantially water column which will prevent the flow of steam to the upper portion of the branch supply pipe and valve. The system as thus far described has one objection, that is when the car is taken out of service and the steam supply is disconnected from the car, the water column in pipe 73 may not flow out and may freeze in the exposed portion of the piping. The vent opening 135 is provided to prevent this freez-

ing. During normal operation, with valve G open, some steam will flow in through the vent opening 135. When valve G is closed there will be, as before, an accumulation of water in the riser 73 drawn up by the vacuum formed in this pipe. There will still be an inflow of steam through vent opening 135 but this small flow of steam will be condensed upon contacting the water column in the pipe. The final result will be to prevent any substantial quantity of steam rising in the branch supply pipe to heat the valve structure. When the car is taken out of service and there is no longer a steam supply in pipe C, air will enter through vent 135 so as to break the vacuum and permit the water-column to flow out. There will always remain a small accumulation of water in the pool 130, but it will be noticed that the bottom of this pool is rounded so that no damage will result from the freezing of this small quantity of water.

The steam-retarder D (Figs. 1 and 10) is formed with a threaded inlet port 136 receiving the threaded end of supply pipe C, and opening into the steam chamber 137. An internal web 138 separates steam chamber 137 from the outlet chamber 139 which has an outlet port 140 which receives the threaded end of return pipe K. The annular collar member 141 threaded into a vertical passage in web 138 surrounds the fluid-passage 142 connecting chambers 137 and 139. An upwardly projecting rounded bead 143 forms a valve-seat surrounding the upper end of passage 142, this valve seat being engaged by the movable valve member 144 when chamber 137 is filled with steam so as to expand the sensitive thermostatic bellows 145. The upper fixed end of this bellows is carried by the closure 146 removably attached to the upper end of the main casting of the retarder. As long as the supply pipe C and chamber 137 are filled with steam, the bellows 145 will expand so as to hold back this steam and prevent the flow of any substantial amount into the return pipe K. However, when any condensate accumulates in the end portion of supply pipe C the bellows 145 will contract sufficiently to lift the valve 144 and permit this condensate to flow out into chamber 139 and thence through return pipe K. It will be noted that one or more small notches 147 are formed in the valve-seat 143, these notches permitting a very restricted flow of steam into the return pipe at all times, even though the valve 144 is closed. This is for the purpose of keeping the return pipe K warm as will be hereinafter referred to again.

The steam retarders or traps J (Fig. 1) are substantially the same as the retarder D shown in Fig. 10, the only change being that the annular valve-seat 148 shown in Fig. 11 is substituted for the larger valve-seat 141 shown in Fig. 10. It will be noted that the central steam passage 149 is considerably smaller than the passage 142 in the previously described annular member 141, and the upstanding annular valve-seat 150 is of considerably less diameter than the similar valve-seat 143 of Fig. 10. Steam and condensate from the radiator F and valve G flow out through pipe 68 into chamber 137 of the retarder or trap, and sufficient condensate will cause the bellows 145 to contract and let the condensate flow out through the section 68' of this branch return pipe into the main return pipe K. By providing a smaller valve-seat 150 there will be an increased total upward pressure against the lower end of the bellows 145 and tending to open the valve when closed so that the retarder

or trap J will be more sensitive than the trap D first described and will open more often and more quickly and at a higher temperature to permit the drainage of condensate from the radiators. At the same time the traps will close quickly but quietly so as to prevent the loss of any substantial amount of steam and also to prevent the excessive loss of steam pressure at these retarders J.

The condensate and non-condensable gases collected in main return pipe K through the retarders D and J flow from the lower end of return pipe K through connection 151 into the upper end of the drip pipe L which is open to the atmosphere at its lower end. This drip pipe is preferably covered with insulation 152 so as to retain heat and prevent, so far as possible, the freezing of liquid in this drip pipe. Another pipe connection 153 extends from the outlet port 42' of the thermostatic chamber 21 of the steam regulator B into the upper end of drip pipe L so that all condensate from the heating system will be discharged through this same protected drip pipe L.

It will now be noted that there will be a limited amount of steam flowing from the regulator B through the discharge pipe 153, and also from each of the radiating systems when the traps J are open, and this steam will ordinarily be sufficient to maintain these pipes above a freezing temperature. However, if the return pipe K is very long it is desirable to permit a limited flow of steam into this pipe to prevent water from freezing therein and it is for this reason that the open notch or passage 147 is provided in the valve-seat 143 of retarder D. This small steam flow will be enough to maintain the pipe K above freezing temperature. The steam admitted from all of these sources will also tend to keep the interior of drip pipe L above the freezing temperature. It will be understood that the righthand end of the supply and return pipe loop shown in Fig. 1 is cut away and that there will ordinarily be several more radiators F supplied with steam from this loop, thus making the desirability of supplying a limited flow of steam to the return pipe K more apparent.

Referring now to the modification shown in Fig. 2 it will be noted that there are only two of the radiating units arranged with their supply and return ends adjacent one another so that the return pipe K is quite short. In this case the end retarder D can be omitted entirely. The steam pressure throughout the system, including supply pipe C, will be kept up by the retarders J. Any condensate accumulating in the short supply pipe C can be blown out through the righthand radiating unit and returned through this unit and the return pipe K. Sufficient steam to keep the return system from freezing will be supplied by the two branch return systems and the return from steam regulator B. Practice has indicated that the retarder D with its restricted steam flow will not be required provided the return pipe K is not over about three feet in length. One notch 147 in the valve seat of retarder D will permit a sufficient steam flow for a return pipe K not over ten feet in length. If the pipe K is longer than this, an additional notch 147 or a larger notch should be used.

It will now be apparent that this steam heating system, while resembling the ordinary vapor-heating system in some respects, differs materially therefrom in operation. In the ordinary vapor heating system, although the discharge end of this system is open to the atmosphere, it is necessary to maintain a material pressure at

the inlet end of the system in order to overcome the quite considerable internal resistance when a plurality of separate radiators are arranged in series. In the improved system here disclosed each radiator or radiating unit draws its steam individually from the same supply pipe and only sufficient pressure to force steam through this single radiator or radiating system is required. It is, however, desirable to maintain the supply pipe full of steam at all times under this desirable low pressure, despite the fact that the number of separate radiating units in service may be continually changing. For this reason a very sensitive steam-regulator B is necessary, and it is desirable not to return fluids from the system to this regulator in order not to disturb the balanced operation thereof. The retarders D and J hold back the outflow of steam so that a steam pressure considerably higher than necessary could be built up in the supply pipe C and the separating units. However, the pressure-limit valve E will open whenever this steam pressure rises above the desired maximum, and the small flow of steam thus returned directly to the thermostatic chamber of the regulator B will serve to throttle the control valve of this regulator so that just sufficient steam will flow from the source into the supply pipe C to replace the steam that is withdrawn, at the desired low pressure, to satisfy the needs of the radiators in service at any one time. If a radiator is added to the system (by the opening of its valve G) there will be an increase in the withdrawal of steam from supply pipe C and the valve of regulator B must be opened an additional amount to compensate for this increased load and at the same time keep the pressure in pipe C up to the desired maximum, for example five pounds. This is automatically accomplished by the balancing action of the regulator B and the pressure-limit valve E, and is not influenced in any way by fluids returned from the radiating system. Should returning condensate be allowed to flow to the thermostatic chamber of the regulator, the action of the regulator would be so irregular as to cause prolonged periods of inactivity with a consequent "starving" of the radiators. In the present improved system, the thermostatic element of the regulator is controlled entirely and directly by pressure changes in the supply pipe C, and is not influenced or disturbed in any way by permitting cold fluids returned from the radiating systems to come near the controlling thermostatic member. Experience has shown that this improved type of heating system makes for greater economy because, with the various valves of generous size and the resistance through the system decreased due to parallel feeding, steam can flow through easily and quickly when only a small pressure differential is provided between the inlets and outlets of the respective radiating systems. This small but relatively constant pressure differential is kept up at all times by the steam supply system disclosed hereinabove.

We claim:

1. In a controlled volume steam heating system, a source of relatively high pressure steam, a steam supply pipe, a valved connection between the source and supply pipe, means controlled automatically in response to pressure-changes in the supply pipe to open or close the valved connection whereby the supply pipe is kept filled with steam at a predetermined low pressure, a plurality of radiators, and means for independ-

ently supplying each radiator with steam from the supply pipe, a drain connection having branches leading from each radiator and from the supply pipe, thermostatically operating steam retarder means in each branch drain connection, the retarder means between the supply pipe and the drain including a constantly open orifice to permit a small flow of steam into the drain connections to prevent freezing of fluid therein.

2. In a controlled volume steam heating system, a plurality of independently operating radiating systems each comprising a radiator, branch supply and return pipes leading to and from the radiator, an inlet valve in the supply pipe, and a steam-trap in the return pipe, a main supply pipe from which all of the branch supply pipes lead separately, a main source of steam, means comprising a steam-regulator for continuously maintaining a supply of steam from the source in the main supply pipe at a predetermined low but super-atmospheric pressure, said regulator comprising a valve and a thermostatic member for throttling the valve, means actuated by pressure-changes in the supply pipe for feeding steam to the thermostatic member, a drip pipe, a return main into which the branch return pipes discharge, and a discharge pipe leading from the regulator, both the latter discharge pipe and the return main discharging condensate through the drip pipe.

3. In a controlled volume steam heating system, a source of relatively high pressure steam, a regulator comprising an inlet chamber communicating with the source, an outlet chamber, a valve controlling the flow from the inlet chamber to the outlet chamber, a thermostat chamber, a thermostatic member in the thermostat chamber, connections for adjusting the valve to restrict the flow of steam as the thermostatic member is exposed to steam temperature, a conduit connection leading from the outlet chamber to the thermostat chamber, a normally closed valve in this conduit adapted to open when the pressure in the outlet chamber rises above a desired maximum, a supply pipe leading from the outlet chamber, a drip member connected at its upper inlet end with the thermostat chamber and at its lower outlet end with the atmosphere, a plurality of radiating devices, an inlet valve for each radiating device, a riser leading from the supply pipe to each inlet valve, a condensate return pipe leading into the drip member, branch return pipes leading from each radiating device into the main return pipe, and steam traps positioned one in each branch return pipe.

4. In a controlled volume steam heating system, a source of relatively high pressure steam, a regulator comprising an inlet chamber communicating with the source, an outlet chamber, a valve controlling the flow from the inlet chamber to the outlet chamber, a thermostat chamber, a thermostatic member in the thermostat chamber, connections for adjusting the valve to restrict the flow of steam as the thermostatic member is exposed to steam temperature, a conduit connection leading from the outlet chamber to the thermostat chamber, a normally closed valve in this conduit adapted to open when the pressure in the outlet chamber rises above a desired maximum, a supply pipe leading from the outlet chamber, a drip member connected at its upper inlet end with the thermostat chamber and at its lower outlet end with the atmosphere, a plurality of radiating devices for independently

heating separate spaces, an inlet valve for each radiating device, thermostatic means for independently opening or closing each inlet valve in response to temperature changes in the space heated by the individual radiating device, a riser leading from the supply pipe to each inlet valve, a condensate return pipe leading into the drip member, branch return pipes leading from each radiating device into the main return pipe, and steam-traps positioned one in each branch return pipe.

5. In a controlled volume steam heating system, a source of relatively high pressure steam, a regulator comprising an inlet chamber communicating with the source, an outlet chamber, a valve controlling the flow from the inlet chamber to the outlet chamber, a thermostat chamber, a thermostatic member in the thermostat chamber, connections for adjusting the valve to restrict the flow of steam as the thermostatic member is exposed to steam temperature, a conduit connection leading from the outlet chamber to the thermostat chamber, a normally closed valve in this conduit adapted to open when the pressure in the outlet chamber rises above a desired maximum, a supply pipe leading from the outlet chamber, a drip member connected at its upper inlet end with the thermostat chamber and at its lower outlet end with the atmosphere, a plurality of radiating devices, an inlet valve for each radiating device, a riser leading from the supply pipe to each inlet valve, a condensate return pipe leading into the drip member, branch return pipes leading from each radiating device into the main return pipe, steam-traps positioned one in each branch return pipe, and a steam-trap between the outlet end of the supply pipe and the return pipe, said last-mentioned trap having a constantly open restricted passage to permit a small continuous flow of steam into the return pipe.

6. In a steam heating system, a steam supply pipe, a radiator positioned at a higher level, an inlet valve at one end of the radiator, a water-seal fitting connected in the supply pipe and adapted to accumulate a pool of water in the lower portion of the fitting, a chamber formed in the upper portion of the fitting having an upper outlet port and having an inlet opening in its bottom leading from below the water-level, the fitting providing for a free flow of steam through the supply pipe above the water level and past the chamber, and a steam-riser leading from the outlet port of the chamber up to the inlet valve, there being a small fluid passage connecting the supply pipe with the chamber above the water level.

7. In a steam heating system, a steam supply pipe, a radiator positioned at a higher level, an inlet valve at one end of the radiator, a water-seal fitting connected in the supply pipe and adapted to accumulate a pool of water in the lower portion of the fitting, and a conduit leading from below the water-level of the pool up to the inlet valve there being a small fluid passage in the side wall of the lower portion of the conduit above the water-level, but within the fitting.

8. In a low pressure steam heating system, a source of steam, a supply pipe receiving steam from the source, a return pipe, a plurality of radiators each receiving steam from the supply pipe at different locations between its inlet and outlet ends and returning condensate to the return pipe at locations between its inlet and out-

let ends, and a restricting valve connecting the outlet end of the supply pipe and the inlet end of the return pipe, the valve comprising a constantly open small orifice and a normally closed large orifice, a closure for the large orifice thermostatically moved to closed position when exposed to steam in the supply pipe, the small orifice admitting only sufficient steam to the return pipe to maintain this pipe and its liquid contents above freezing temperature.

9. In a low pressure steam heating system, a source of steam, a supply pipe receiving steam from the source, a return pipe, a plurality of radiators each receiving steam from the supply pipe at different locations between its inlet and outlet ends and returning condensate to the return pipe at locations between its inlet and outlet ends, and a restricting valve connecting the outlet end of the supply pipe and the inlet end of the return pipe, the valve comprising a constantly open small orifice and a normally closed large orifice, a thermostatic bellows positioned in the path of the steam in the supply pipe and serving at its closed movable end as a closure for the large orifice, the small orifice admitting

only sufficient steam to the return pipe to maintain the return pipe and its liquid contents above freezing temperature.

10. In a low pressure steam heating system, a source of steam, a supply pipe receiving steam from the source, a return pipe, a plurality of radiators each receiving steam from the supply pipe at different locations between its inlet and outlet ends and returning condensate to the return pipe at locations between its inlet and outlet ends, and a restricting valve connecting the outlet end of the supply pipe and the inlet end of the return pipe, the valve comprising a large orifice with a valve seat at its inlet end, a closure adapted to engage the valve-seat, a thermostatic member actuated by steam in the supply pipe to move the closure to seat-engaging position, there being a constantly open notch formed in the valve-seat for permitting a limited flow of steam therethrough at all times to maintain the return pipe and its liquid contents above freezing temperature.
